INSULATOR BRACKET

L. E. Lindsey, 222 Vista Ave., Pasadena, Calif.

Filed May 24, 1965, Ser. No. 85,434

Term of patent 14 years

(Cl. D54—1)

FIGURE 1 is a side elevational view of an insulator bracket embodying my new design;

FIGURE 2 is an elevational view of the front face of the insulator bracket;

FIGURE 3 is a side elevational view of the side of the insulator bracket opposite that shown in FIGURE 1;

FIGURE 4 is an elevational view of the rear face of the insulator bracket;

FIGURE 5 is a top plan view of the insulator bracket; and

FIGURE 6 is a cross-sectional view of the insulator bracket taken along line 6—6 on FIGURE 2.

The fragmentary insulator and pole shown in FIGURE 1 in broken lines are for illustrative purposes only.

I claim:

The ornamental design for an insulator bracket, as shown and described.
